UNITED STATES PATENT OFFICE.

ORRIN M. ROLFE, OF LOWELL, MASSACHUSETTS.

HEEL-CUSHION FOR BOOTS AND SHOES.

1,154,340.

Specification of Letters Patent.

Patented Sept. 21, 1915.

Application filed July 26, 1915. Serial No. 41,860.

To all whom it may concern:

Be it known that I, ORRIN M. ROLFE, a citizen of the United States, residing at Lowell, in the county of Middlesex and 5 Commonwealth of Massachusetts, have invented a certain new and useful Improvement in Heel-Cushions for Boots and Shoes, of which the following is a specification.

This invention relates to heel-cushions for 10 boots and shoes of ordinary construction, such cushions being adapted to be readily placed within the boots or shoes and as readily to be removed therefrom, and in use being retained in position by the relative shape 15 of the cushion and of the boot or shoe in which they are worn.

The cushion herein described is made of thin spring sheet-metal, preferably spring sheet-steel and is provided at its side edges 20 with downwardly curved fingers integral with said plate and convex on their outer surfaces, so that the pressure of the foot upon said plate not only concaves the upper surface of said plate between its sides but 25 increases the curvature of the spring fingers, thus utilizing the elasticity of both the body of said plate and of said fingers. The lower end-portions of the fingers, rest upon a metallic or wear-resisting bearing-plate 30 which is provided with upturned side edges outside of the lower parts of said fingers, to keep said fingers from getting off said bearing plate and wearing the sole of the shoe. The top plate and the bearing plate are connected at or near their front ends, to prevent any lateral or longitudinal movement 35 of either relatively to the other. A sheet of leather or any similar comparatively soft material may be arranged above the top 40 plate and secured in place by rivets which pass through said sheet and the top-plate and wearing-plate.

In the accompanying drawing, Figure 1, is a plan of any improved heel-cushion; Fig. 45 2, a right side elevation of the same; Fig. 3, a rear elevation of the same; Fig. 4, an isometric perspective view of the same with the unattached rear end of the lining turned up and the rear end portion of the top-plate 50 broken away to show the wearing plate; Fig. 5, a longitudinal section of a part of a boot or shoe, showing the cushion in position.

A denotes the top-plate, of the general 55 contour in plan of the rear portion of the

insole e of the shoe and arranged in use above the heel e¹ and extending for some distance forward over the shank of the shoe, except that the side edges of said top-plate are provided with arc-shaped fingers a a¹ 60 integral with said top-plate and curved outwardly beyond the sides and downwardly, as best shown in Fig. 3, said plate A and fingers being formed from thin spring sheet-steel. The body of the wearing plate B is of 65 the same sheet spring material as the top-plate and has the general form of the body of the top-plate but is provided with upturned side edges b b¹ which reach up on the outside of the spring fingers and act as 70 stops to limit the lateral outward movement of said fingers and prevent said fingers from getting over the side edges of said plate B and marring the top of the in-sole of the shoe. The front end portions of the plates 75 A and B are secured to each other, as by rivets D. A lining B of leather, felt cloth or other comparatively soft material is represented as covering the top-plate and secured in place by the same rivets D which unite 80 the plates A and B, said rivets passing down through lining and plates.

When the cushion is in place the pressure of the foot depresses the middle of the plate and also compresses the springs and the 85 greater thickness of the rear end of the cushion tends to force it backward and the greater width of the rear portion of the cushion and the front ends laterally projecting tops b b¹ of the wearing plate keep said 90 cushion from sliding forward. The pressure of the foot presses the top-plate A down upon the wearing plate B and forces the middle portion of the latter down into the central depression in the top of the in-sole 95 over the heel.

I claim as my invention;

1. A heel-cushion comprising a top-plate of spring sheet-material having at its side edges downwardly curved fingers integral with said plate, and a wearing plate having upturned side edges outside of the lower ends of said fingers, said plates being secured to each other near their front ends. 100

2. A heel cushion comprising a top-plate of spring sheet-material having at its side edges downwardly curved fingers integral with said plate, and a wearing plate of spring-sheet material, having upturned side edges outside the lower ends of said fingers, 105 110

said plates being secured to each other near their front ends.

3. A heel cushion, comprising a top-plate of spring sheet steel having at its side edges downwardly curved fingers integral with said plate, and a wearing plate of spring sheet steel on which the lower ends of said fingers rest said wearing plate having upturned side edges outside the lower ends of

said fingers, said plates being secured to each other near their front ends.

In witness whereof, I have affixed my signature in presence of two witnesses.

ORRIN M. ROLFE.

Witnesses:

ALBERT M. MOORE,
PHILIPPE PROVENCHER.
